UNITED STATES PATENT OFFICE.

KIHEI KOIKE, OF SEATTLE, WASHINGTON.

PROJECTING APPARATUS.

1,072,861.

Specification of Letters Patent. Patented Sept. 9, 1913.

Application filed November 29, 1911. Serial No. 663,154.

To all whom it may concern:

Be it known that I, KIHEI KOIKE, a subject of the Emperor of Japan, and a resident of the city of Seattle, in the county of King and State of Washington, have invented certain new and useful Improvements in Projecting Apparatus, of which the following is a specification.

My invention relates to apparatus of the above type, having more particular reference to such apparatus designed for the projection of opaque objects, and has for a fundamental object the provision of a novel mechanism for advancing and supporting the slides or plates bearing the subject matter for display.

Other objects will be set forth as my description progresses and those features of construction, arrangements and combinations of parts on which I desire protection, succinctly defined in my annexed claim.

Referring to the accompanying drawing wherein like numerals of reference indicate like parts throughout the several views: Figure 1 is a longitudinal section of my apparatus taken on line 1—1 of Fig. 2, and Fig. 2 is a top plan in partial section.

Referring to the drawing by numerals of reference, 1 indicates a rotary carrier for advancing the slides or plates 2 into the field of display, the said carrier, being also employed to hold the plates in their displaying position which, as now considered, is across an opening 3 of a casing 4, so that the slides can be covered by the light shafts from a suitable source of light, as lamps 5.

Reference numeral 6 indicates the objective, arranged opposite opening 3 and through which the light reflected from a slide 2 passes to the screen, not shown, as is well understood.

Slides or plates 2, which are of opaque form, are conventionally mounted in frames 2', which latter are each pivotally connected with those on either side thereof by pintles 2'', engaged in suitable tubular edge extensions 7 of frames 2', as clearly shown in Fig. 2. Every alternate pintle 2'' is of greater length than the others, the same having their end portions projecting outwardly therebeyond for engagement with suitable rails or tracks 10, underlying and projecting on opposite sides of rotary carrier 1 and inclined downwardly toward the rear side thereof, thus permitting of the intermediate pairs of slide frames 2',

or those frames connected by the shorter pintles to fold downwardly between the rails 10, as shown in Fig. 1. The projecting end portions of the long pintles 2'' are conveniently provided with rollers 11, these serving to support the folded slide frames on rails 10 for movement by gravity thereon toward the end stops 10', thus insuring of upper end portions of the tracks being maintained in a properly cleared condition for reception of those slide frames being moved from their displaying position.

Carrier 1 comprises side members 1', fixed to a shaft 12 journaled in bracket arms 13 of casing 4, the said side members being formed with peripheral seats 15 for reception of rollers 11, and intermediate cross bars 16, which latter extend between side members 1' to provide bearings for those end portions of the slide frames joined by the short pintles. Carrier 1 is driven intermittently by the mechanism now to be described.

Reference numeral 17 indicates a belt taking over pulleys 12' and 12'' of shafts 12, and 18 respectively, and also over suitable direction sheaves 19, the said shaft 18 being journaled in a suitable housing 20, underlying casing 4, and connected with a drive shaft 21 through a well known type of gearing comprising the single tooth gear 22 and slotted wheel 23, the former of which is fixed to said drive shaft 21. Drive shaft 21 is connected, as through the medium of worm gearing 24 with a motor 25 to receive continuous rotary motion therefrom.

In the operation of my invention, carrier 1 during its intermittent movement elevates the slides from the lower end portions of rails 10, then moves the same in front of casing opening 3, said carrier simultaneously with the positioning of a slide in said last named position, coming to a stop or pause. During further rotation of carrier 1, the exposed slide is lowered to rails 10, as hereinbefore set forth. By extending the lower end portions of rails 10 beyond carrier 1, frames 2' are unfolded and drawn upwardly in a straight path toward which the lower half portion of the upwardly moving side of carrier 1 advances (see Fig. 1) thereby insuring of the unfolded upwardly moving frames being held practically taut for a perfect seating on the carrier.

Having thus described my invention, what I claim as new, and desire to secure by Let-

ters Patent of the United States of America,
is:

In apparatus of the character described, a plurality of slide frames each hinged at its opposite edges to the adjacent frames on either side thereof, the pintles of alternate hinge connections being longer than the others, rotatable means for moving said slide frames past said projection device and between said rails, said means comprising spaced rotary members provided with alternating seats and cross bearing members, the said seats being adapted to receive the projecting end portions of said long pintles, and said bearing members being spaced with respect to said seats to support the opposite

end portions of said slide frames, spaced rails lying in the path of the projecting end portions of said long pintles, said rails being below and projecting on opposite sides of said rotatable means and inclined downwardly and beyond the upwardly moving side thereof, a projecting device at the downwardly moving side of said rotatable means, and means for rotating said rotatable means.

Signed at Seattle, Washington this 21st day of November 1911.

KIHEI KOIKE.
